UNITED STATES PATENT OFFICE.

ALBERT J. LOGAN AND JOHN FRANKLIN BROWN, OF PITTSBURG, PENNSYLVANIA.

SPRING BED-BOTTOM.

SPECIFICATION forming part of Letters Patent No. 760,746, dated May 24, 1904.

Application filed November 4, 1903. Serial No. 179,855. (No model.)

To all whom it may concern:

Be it known that we, ALBERT J. LOGAN and JOHN FRANKLIN BROWN, residents of Pittsburgh, in the county of Allegheny and State 5 of Pennsylvania, have invented a new and useful Improvement in Spring Bed-Bottoms; and we do hereby declare the following to be a full, clear, and exact description thereof.

Our invention relates to a base or support 10 for spiral or helical springs for use in beds, couches, seats, and the like. Its object is to provide a strong rigid base and a manner of attaching the springs to the same in a neater, more secure, and economical way than has 15 heretofore been accomplished.

In the accompanying drawings, Figure 1 is a plan view of a portion of the bed-bottom constructed according to our invention. Fig. 2 is an end view of the same. Figs. 3 and 4 are opposite side views showing the manner of applying the springs thereto. Fig. 5 is a section on the line 5 5, Fig. 1. Fig. 6 is a similar section on the line 6 6, Fig. 1. Fig. 7 is a bottom view of one of the cross members or slats, showing the manner of applying the spring thereto. Fig. 8 is a detail view showing the manner of applying the cross-bars to the side members, and Fig. 9 is a plan view of the blank from which the cross-bars 25 are formed.

Spring bed-bottoms provided with metal bases should be light in weight and should also be made in sections to permit easy handling thereof and to prolong the life or usefulness of the springs. A spring bed-bottom made in three interchangeable sections can be easily handled and will outlast three one-piece bottoms made in the usual manner, for the reason that the damage or depression to 35 the springs invariably occurs at or near the middle of the bed, and therefore unless the middle section can be moved to the head or foot and replaced by one of its fellows the bed-bottom as a whole becomes useless.

Our invention is adapted for making bed-bottoms either in three interchangeable sections or in a single piece. In the drawings only one such section has been shown; but as the other two sections are identical in struc-

ture with the one shown a description of the 50 one will suffice for all, and it will also be readily understood that by merely extending the length of the section shown a one-piece bed-bottom may be formed.

In the drawings the side rails of the bed 55 are shown at 1, these being shown of angle shape, as is common in iron bedsteads. Our improved base or support comprises a series of cross-bars or slats 2, which are of inverted-trough shape, as shown, and suitably secured 60 at their ends to side members 3, the latter being ordinary commercial plates or bars of the desired dimension, and which can be cut off square at their ends either for forming a sectional bottom or extended the entire length 65 of the bed for forming a one-piece bottom. The cross-bars 2 are provided at their ends with shoulders 4, and in assembling these with the side members the latter are brought up firmly against said shoulder, thus forming 70 a rigid base which will not become askew and obviating the necessity of diagonal bracing, thus considerably lightening the same.

The cross-bars 2 are preferably formed of inverted-trough shape, as shown, having the 75 two side portions 5 substantially vertical, so as to very greatly stiffen the same, thus making it possible to use plate metal of very thin gage and greatly lightening the base, but at the same time getting sufficient strength. 80 These cross-bars are made by taking flat plates of the desired width and thickness and first stamping them out at the ends to form the notches 6 and the holes 7, the latter serving for the passage of the rivets 8, which secure 85 said cross-bars to the side members 3. Intermediate their ends the plates are punched with groups of holes of three each 10, 11, and 12. This plate is then either rolled or bent by means of dies into the shape shown in Fig. 90 5, having the two side portions 5 parallel and vertical and being provided with the central projecting ridge 14. After being bent into shape these cross-bars are riveted to the side members in the manner above described, so 95 as to get a rigid base without the use of diagonal bracing.

The springs 15 may be of any form of spiral

or helical springs, those shown in the drawings being of the single-cone type. The lower ends of these springs are secured to the bars by threading the lower wire thereof through the holes in the side walls of said bars, first passing it through the hole 10, then through the hole 11 in the opposite side wall, and then back again through the hole 12, after which the end is crimped or bent, as at 16, thus preventing said spring from becoming detached; but as this end lies in the trough-shaped bar it is out of the way and cannot tear the bedding or otherwise be objectionable.

At the tops the springs may be connected by any suitable device known for this purpose, that shown in Fig. 1 being the same as that covered by Letters Patent to John Franklin Brown, No. 704,674, dated July 15, 1902; but as it is not claimed herein it need not be described.

It will be observed that the base described is simple of construction, strong, and very light. The shape of the cross-bars, having the two side walls thereof substantially vertical, gives the necessary strength so that very thin gage metal can be used, and at the same time they form a suitable place for the holes into which the springs are threaded. The central ridge 14 furthermore is made of a height somewhat greater than the distance between adjacent coils of the springs, so that when the latter are threaded into place this ridge serves to hold the two lower coils somewhat spread apart, as indicated in Fig. 5, thus holding the second coil 17 under tension and obviating the possibility of vibration and rattling. The cross members are all identical, and the side members are formed of ordinary flat commercial metal, so that only two shapes of iron are used and the connection between these being such that diagonal bracing is dispensed with.

We of course are aware that spring-bottoms have heretofore been made in sections; but each section has required additional material and labor, thus adding to the cost of the same. With our base, however, the construction is such that a sectional base can be made just as economically as a one-part base, it merely being necessary to cut the side members 2 into sections, this being the only additional labor on a sectional base over that of a one-part base.

What we claim is—

1. A base or support for the springs of beds and the like comprising side members, metallic cross members of inverted-trough form

from end to end, said cross members having their side walls cut away at the ends and having their curved top portions projecting over the side members, means for securing said projecting end portions to the side members, and coiled springs supported by said cross members.

2. A base or support for the springs of beds and the like comprising side members, metallic cross members of inverted-trough form from end to end, said cross members having their side walls cut away at the ends to form vertical shoulders and having the projecting portions extending over the side members with the vertical shoulders bearing against the side members, means for securing said projecting end portions to the side members, and springs supported by said cross members.

3. A base or support for the springs of beds and the like comprising a series of metallic cross-bars of inverted-trough form provided with holes in the sides thereof and a longitudinal ridge on their upper sides, a series of springs threaded through the holes in said bars and having one coil thereof pressed upwardly by said ridge and having their ends bent over inside of said trough-like cross-bars, and side members to which said cross-bars are secured.

4. A base or support for the springs of beds or the like, comprising a series of metallic cross-bars of inverted-trough form provided with holes in the sides thereof and a longitudinal ridge on their upper surfaces, a series of springs threaded through the holes in said bars and having one coil thereof pressed upwardly by said ridge, and side members to which said cross-bars are connected.

5. A base or support for the springs of beds and the like, comprising a series of metallic cross-bars or slats of inverted-trough form from end to end and having vertical side walls provided with groups of holes therethrough and with vertical shoulders at their ends, and having end portions projecting beyond said shoulders, side members secured to the projecting ends of said cross-bars and bearing against the shoulders of the latter, and springs threaded through the holes in said cross-bars.

In testimony whereof we, the said ALBERT J. LOGAN and JOHN FRANKLIN BROWN, have hereunto set our hands.

ALBERT J. LOGAN.

JOHN FRANKLIN BROWN.
